UNITED STATES PATENT OFFICE.

TEAFORD C. SHEPPARD, OF SOUTH RICHMOND, VIRGINIA.

MAIL-BAG.

1,354,581.

Specification of Letters Patent.

Patented Oct. 5, 1920.

Application filed May 22, 1920. Serial No. 383,453.

To all whom it may concern:

Be it known that I, TEAFORD C. SHEPPARD, a citizen of the United States, residing at South Richmond, in the county of Henrico and State of Virginia, have invented certain new and useful Improvements in Mail-Bags, of which the following is a specification, reference being had to the accompanying drawing.

- 10 This invention relates to an improved mail bag adapted for use by mail carriers, and an object is to provide an improved locking means for holding the closure secure.
- 15 Another object is the provision of a locking means for mail bags, wherein a plurality of auxiliary swivelly mounted locking members are employed to enter slotted plates of the closure of the mail bag, and
- 20 also wherein a reciprocating element common to all of the locking members is employed for moving the members so that they may enter or be withdrawn from the slotted plates of the closure in combination with
- 25 means for locking the reciprocating element, when the closure is closed.

Heretofore locking members of the character shown have been employed and also in connection with a reciprocating element common to all of the locking members for actuating them, but such reciprocating elements heretofore used are guided so that there is no movement of the element permitted transversely of the reciprocating movement, and in this case it has been necessary heretofore to use slot connections with the links carried by the locking members to permit the links to be oscillated by the reciprocating element. Furthermore, in these

35 locking devices heretofore employed the reciprocating elements are in the form of a metallic bar, hence rendering it necessary to provide the slot connections with the links.

In the present device it is the aim to overcome these disadvantages and to provide a flexible or pliable reciprocating element mounted in a guide of the mail bag and being pivoted direct to the links, so as to lock and unlock the locking members, and in this

40 device the reciprocating element is capable of movement laterally to the longitudinal movement of the element so as to permit the locking members to be moved.

A further object is the provision of a mail bag including a novel form of locking means, therefor, which is capable of being

cheaply manufactured and sold at a reasonable profit, and one which has been found simple, efficient and practical in construction.

60 While the design and construction at present illustrated and set forth is deemed preferable, it is obvious that as a result of a reduction of the invention to a more practical form for commercial purposes, the invention 65 may be susceptible to changes, and the right to these changes is claimed, provided they are comprehended within the scope of what is claimed.

70 The invention comprises further features and combination of parts, as will be herein-after set forth, shown in the drawings and claimed.

In the drawings:—

75 Figure 1 is a view in elevation of the improved mail bag constructed in accordance with the invention, showing the locking mechanism applied and constructed in accordance with the invention;

80 Fig. 2 is a view in elevation showing the flap open thereby clearly showing the locking mechanism and the locking members in an unlocked position.

85 Fig. 3 is a sectional view through the mail bag showing the locking members in an unlocked position so that the flap can be opened.

90 Fig. 4 is a detail perspective view of a portion of the reciprocating member.

Referring to the drawings, 1 designates 90 a mail bag which may be any suitable or conventional form or construction, and is provided with an opening 2, whereby access may be had to the interior of the bag. One side of the mail bag has a closure flap 3 95 which is provided with a plurality of slots 4, and adjacent the exterior surface of the flap 3 are shield plates 5 also having slots 6 conforming to the slots in the leather closure flap. In fact the mail bag may be constructed of any suitable material preferably leather or the like, therefore, it is necessary to line the slots in the closure flap. These shield plates are riveted at 7 to the closure so as to hold them in place. The other side 100 105 of the mail bag has the edge adjacent the opening terminating in an extension 8 which is folded over adjacent the side of the mail bag and stitched at 9. This folded part 8 has riveted to its outer face plates 9 provided with openings 11 in which the shanks 12 of the locking members 13 are swivelly mount-

ed. In order to swivelly mount the locking members the shanks are provided with shoulders 14 which engage certain of the riveted plates while the ends of the shanks are swaged as shown at 16 to provide heads. The shanks adjacent the heads, and in fact also the parts engaging through the opening of the riveted plates are rectangular, and connected to the shanks under the heads 5 10 are the ends of the links 17. These links are movable with the shanks of the locking members and furthermore they are movable in planes parallel to each other. These links are in turn pivotally connected to a reciprocating element as at 18. This reciprocating element 19 is constructed of any suitable material preferably pliable material such as heavy leather and is mounted under the folded part 8 of the side of the mail bag. 15 20 One end of the reciprocating element extends beyond one of the ends of the folded part 8 beyond the end stitching of the folded part 8 while the other end 20 extends through the slot or slit 21 of the folded part 8.

The end 20 of the reciprocating element is provided with a slot 22 and engaging the opposite faces of the element adjacent the slot 22 are shield plates 23 which are riveted 30 to the end 20 of the element. These shield plates have slots 24 registering with the slot of the reciprocating element and by means of the shield plates such end of the reciprocating element is stiffened and reinforced. 35 A plate is mounted on the outer face of the folded part 8 and passing through this plate 25 and through the folded part and the side of the mail bag are rivets 26 thereby securely riveting the plate in place. A 40 staple 27 is provided and is projected laterally from the plate 25. The arms of the staple have their ends reduced and pass through the plate 25 and through a plate 28 on the inner surface of the side of the mail bag. 45 The ends of the reduced parts of the arms of the staple are swaged thereby forming heads, hence holding the staple rigidly and as extending laterally from the plate 25. The staple is disposed at right angles to the 50 normal or unlocked positions of the locking members, and is designed to pass through the slots of the plates 23, to hold the reciprocating element in a position which causes the locking elements to assume a corresponding locking position, after they have entered 55 through the slots 5 and 6 of the closure flap and the plates which are carried by the flap. The flap at one end has a shield plate lined slot 29 through which the staple also engages and when so engaged a shackle of a 60

conventional form of padlock may engage the staple and hold the flap closed. The padlock is designated by the numeral 30 and may be any suitable construction. The shield plate 31 of the shield plate lined slot 65 of the flap is riveted at 32 to the closure flap.

Suitable links 33 are connected to one side of bag by means of the loop straps 34 and connected to the links 33 is a shoulder strap 35. The shoulder strap is connected to the 70 links by a conventional form of snap hook as illustrated.

The locking members are T-shaped and it will be noted that when the reciprocating element is moved in one direction the heads 75 37 of the T-shaped locking members aline with the slots of the closure flap so as to permit the heads to pass therethrough and when the reciprocating element is moved in the opposite direction, the elements are disposed 80 so that the heads will overlie the slots at right angles to the slots thereby holding the flap in a closed position. It will be noted that the reciprocating element is constructed so as to conform to the mail bag and in order 85 to flex and conform to the body of the carrier. One end of the reciprocating element has an opening 38 through which the finger or thumb of the hand may engage for removing the reciprocating element in one direction or the other.

The invention having been set forth, what is claimed as new and useful is:

In a locking mechanism for mail bag closure flaps, a mail bag having an opening 95 and a closure flap therefor provided with a plurality of reinforced slots, a plurality of locking members on one side of the bag near the opening, means including reinforcing plates swivelly mounting said locking members on the side of the bag, said locking members when positioned to aline with the reinforced slots of the flap, adapted to pass through the slots, a plurality of links connected to and movable with the swivelly 100 mounted ends of the locking members, a pliable strip mounted for reciprocating movement in the side of the bag, which carries the locking members and being movable bodily in a direction toward and from the 105 locking members, and means operatively connecting the links to the strap, and means for locking the strap when it has moved bodily toward the locking members to hold the locking members at right angles to the 110 slots after passing therethrough.

In testimony whereof I hereunto affix my signature.

TEAFORD C. SHEPPARD.
